UNITED STATES PATENT OFFICE

105,137

DESIGN FOR COMBINED FLUSH TANK FOR TOILETS AND COVER THEREFOR

Bernard B. Pieslak, Abingdon, Ill., assignor to
Abingdon Sanitary Mfg. Co., Abingdon, Ill., a
corporation of Illinois

Application October 19, 1936, Serial No. 65,362

Term of patent 7 years

To all whom it may concern:

Be it known that I, Bernard B. Pieslak, a citizen of the United States, residing at 203 Swartz Street, in the city of Abingdon, in the county of Knox and State of Illinois, have invented a new, original, and ornamental Design for a Combined Flush Tank for Toilets and Cover Therefor, of which the following is a specification, reference being had to the accompanying drawing, forming part thereof.

Fig. 1 is a perspective view in elevation of a combined flush tank for toilets and cover therefor, showing my new design;

Fig. 2 is a plan view of a half end portion of said cover;

Fig. 3 is a top plan view of the flush tank, with the cover removed, and

Fig. 4 is a sectional view in elevation of my combined flush tank for toilets and cover therefor, taken on the lines 4—4 of Fig. 1.

The dominant feature of the instant design is the provision of a flush tank having a substantially rectangular bottom wall, the front wall of the tank having an upwardly and rearwardly inclined panel which latter extends from the forward straight edge of the bottom wall and gradually and progressively merges towards its upper edge into a convex configuration when viewed in plan.

I claim:

The ornamental design for a combined flush tank for toilets and cover therefor, as shown and described.

BERNARD B. PIESLAK.
